(57) **CLAIM**

The ornamental design for a fish tank stand as shown and described.

DESCRIPTION

FIG. 1 is a perspective view of a fish tank stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 1;

FIG. 14 is an enlarged view of portion 14 shown in FIG. 1;

FIG. 15 is an enlarged view of portion 15 shown in FIG. 1;

FIG. 16 is an enlarged view of portion 16 shown in FIG. 1;

FIG. 17 is an enlarged view of portion 17 shown in FIG. 1;

FIG. 18 is an enlarged view of portion 18 shown in FIG. 2;

FIG. 19 is an enlarged view of portion 19 shown in FIG. 2;

FIG. 20 is an enlarged view of portion 20 shown in FIG. 2;

FIG. 21 is an enlarged view of portion 21 shown in FIG. 2;

FIG. 22 is an enlarged view of portion 22 shown in FIG. 2;

FIG. 23 is an enlarged view of portion 23 shown in FIG. 2;

FIG. 24 is an enlarged view of portion 24 shown in FIG. 2;

FIG. 25 is an enlarged view of portion 25 shown in FIG. 2;

FIG. 26 is an enlarged view of portion 26 shown in FIG. 2;

and,

FIG. 27 is an enlarged view of portion 27 shown in FIG. 2.

The broken lines in the drawings depict portions of the fish tank stand that form no part of the claimed design.

The dot-dash broken lines represent boundaries of the enlarged portions and form no part of the claimed design.

FIG. 27 is an enlarged view of portion 27 shown in FIG. 2.

The broken lines in the drawings depict portions of the fish tank stand that form no part of the claimed design.

The dot-dash broken lines represent boundaries of the enlarged portions and form no part of the claimed design.
